CONTAINER CONVEYER AND DISTRIBUTOR

Christian N. Bergmann, Pittsburgh, Pa., assignor
of two-sixths to Charles M. Clarke, Sewickley,
Pa.

Application June 22, 1943, Serial No. 491,771

12 Claims. (Cl. 198—81)

My invention is an improvement in distributing conveyers for containers such as bottles, cans, or the like.

In one arrangement, it is particularly adapted to the art of conveying cylindrical units, as milk bottles, from two sources or stations, to a single station or delivery destination, by merging two rows, or series of unit groups, into one stream or current, by combiner switch mechanism.

Alternately, the construction is also available, by reversal of travel movement of the associated conveyer assembly, whereby to distribute containers, or the like, from one incoming conveyer, to a plurality, as two, delivery conveyers, by the same switch mechanism, operating as a divider.

Generally stated, the present improvement consists of a switch mechanism, interposed between a single conveyer and a plurality, as two, conveyers or sections, operating to combine two incoming series of units into one, or to divide a single series or stream, into two.

The active elements of the switch consist of a pair of laterally movable arms, terminating in fending or guiding terminal portions, adjustable to one side or the other of a merging throat.

It may be used for directing traffic or movement of the units, so as to guide them in moving from a branch conveyer to a single conveyer, while temporarily blocking movement thereto from another branch conveyer, acting as a combiner switch; or alternately, for directing movement of units from a single conveyer or section to either of two delivering sections, while temporarily blocking movement towards the other section, acting as a divider switch.

The pair of laterally movable arms and their terminal portions, are so arranged between two branch conveyers as to direct traffic movement of the units from either or both of the branch conveyers alternately, to such single conveyer. Or, in reverse travel, from such single conveyer, to either of such branch conveyers, in dividing a single stream or column.

With either, the arms are so located and controlled, as by individual springs or the like, that in normal open position, their terminals extend partly across a portion of each branch conveyer path area. Interlocking means are provided whereby, when either arm and its terminal, is moved inwardly by an approaching unit, as in combining action, the other arm is automatically locked in extended position, and vice versa, such other arm being automatically released by retraction of its companion arm, for similar operation at the other side.

In using the switch as a divider, whereby the load of an incoming conveyer is to be distributed to a pair of delivery conveyer sections, the terminals of the arms are brought together and located at one side or the other of the throat, in the form of an end point or horn.

In such reverse travel, for dividing action, the particular active controlling arm and its terminal is positively or initially withdrawn for clearance 10 from the resulting open side of the throat. The other arm remaining extended, and with the terminals together, both act to resist and deflect oncoming units to the lateral open throat passage for movement of units, until the arms are 15 reversed oppositely, for alternating similar guidance.

In the drawings, illustrating appropriate embodiments of the invention:

Fig. 1 is a plan view of an installation comprising a pair of conveyers leading to a single conveyer, and the intervening switch mechanism, as of the combiner type;

Fig. 2 is a view of the switch mechanism in longitudinal section and part elevation, on the line II—II of Fig. 1;

Fig. 3 is a transverse section on the line III—III of Fig. 2, showing both arms extended and released for movement of either;

Fig. 4 is a partial similar transverse section on the same line, but showing one arm as moved inwardly below its locking latch;

Fig. 5 is a similar section on line V—V of Fig. 2, showing the lowered latch in holding engagement with the opposite inactive arm;

Fig. 6 is a partial plan view like Fig. 1, showing the switching arms in normal open position;

Fig. 7 is an isometric view of one of the switch arms, detached;

Fig. 8 is a similar view of one of the locking latches for the arms;

Fig. 9 is a plan view, like Fig. 1, showing the switch when used as a divider.

The present invention is an improvement in 45 that class of conveyer and distributor means, for use as in combiner or divider operation, somewhat similar to that of my prior Patents Nos. 2,108,522 and 2,168,191. It is particularly adapted to conveyance and direction of cylindrical units, as bottles or cans, delivered in limited numbers 50 or groups, from say two conveyers moving the units as from different washers to a common filler, using the switch as a combiner.

The invention is also operable to continuously 55 receive units from either conveyer, and to dis-

tribute them to a common delivery conveyer, as well as intermittently, automatically.

Otherwise, by appropriate adjustment of the switch mechanism, the same construction is available in reverse travel and distribution, as from a common supply conveyer to either of two delivery conveyers, using the switch as a divider, as shall be hereinafter described.

Referring to Figs. 1 and 2, two conveyers A and B, in spaced apart relation or parallelism, lead from any suitable source along each side of a switching section C, to a common delivery conveyer D.

The several conveyers are of conventional type, provided with continuous series of flights 2, having the usual flexibly connected supporting links, carried and driven by standard sprockets and power imparting means at appropriate speeds, not necessarily herein described.

One or both of conveyers A and B may be either straight or connected with a lateral supply feed, as is well known.

When used as a combiner, the bottles or units 3, as supported on the moving flights, are moved over from either side conveyer, across bridge plate 4, between the usual guide rails 5 and 5a—5aa.

The outer guide rails 5 continue as a part of switch section C and converge at each side by portions 6, tapering inwardly towards and providing continuous guiding connection with the standard width guides 5b of delivery conveyer D. Likewise, the inner guides 5a, of the switch section, are deflected inwardly, as at 5aa, providing guiding terminals.

The outer edges and terminals of the swinging arms of the switch are designed to extend beyond the guide terminals 5aa, when open, and to engage the limiting terminals of clearance slots therein.

By such guide bar construction there is thus provided a flaring and tapering throat, communicating between the double conveyer switch section C, and single conveyer D, for guiding movement of units, in either direction.

The switch C comprises a complete separable section, connected, as by overlapping plates 1, with guides 5 and 5a at one end, and with guides 5b respectively, at the other end. The guide plates or bars of the switch section, and beyond, are supported at suitable height above the track-way supports 8, along which the flights pass, by bracing supports 9. The flights are, of course, continuations of the ones of conveyers A and B, in the complete installation.

The inner guides 5a of the switch section provide a mounting for the deflecting arms, as by transverse bridge pieces or cross bars 10 and 11, and upper and lower transverse guide bars 12.

Pivotaly mounted on cross bar 11 at 13, are the pair of laterally swinging arms 14, each having an abruptly projecting and concaved shoulder 15, and an inclined plate or fending shoe 16.

While the fending shoe 16 is shown as a separately attached plate, it may be integral with the arm, of any suitable width, for edge engagement by a unit in transit.

When together, at one side or the other, these shoes brace each other and form a wedge-like assembly, tapering to a practically effective point or dividing horn, tending to divert approaching units towards one side of the expanding throat, when used as a divider switch.

Otherwise, when used as a combiner, as in Fig. 1, with the pair of arms thrust to an opposite side from the side conveying other approaching

units, any approaching units along such opposite side will be retarded and held by the shoulder 15, until such first group of units has passed beyond the shoe terminal. Thereupon, opposite pressure of the retarded group will reverse the position of the arms, allowing for passage of the retarded group, such functioning alternating throughout alternating action of each successive supply. When no units are in passage at either side, the arms are caused to open by springs 17, one for each arm, exerting separating movement of the arms to open position, as in Fig. 6.

The pull of the springs is comparatively weak, subject to adjustment by temper screws 18, to effect free swinging.

Clearance slots 19 are provided in the guide terminals 5aa permitting extreme outward limited movement of each arm, to the slot terminal.

As thus mounted, and with both arms open under tension of springs 17, either arm may be moved inwardly by a contacting unit approaching towards delivery conveyer D, the other arm however being automatically locked in extended position.

For such purpose are provided a pair of transversely and oppositely arranged gravitating latch arms 20, pivoted at 21, having a holding lug or abutment 22 for the inactive extended arm, as in Fig. 4, and a gravity lowering lifting and unlocking cam 23.

Such cam is acted upon by inclined edge face 24 of either bar in its outward movement, raising the latch arm and releasing the other bar for inward movement, as in Fig. 3.

When both bars are spread apart to their normal outward limit, either one may be pressed inwardly by a first unit contact, with simultaneous locking of the other, by lowering of the abutment 22 when the cam supporting other bar 14 is moved inwardly, as in Fig. 5.

Thus inward movement of either arm, by permitting the free cam terminal of arm 20 to fall, will cause abutment 22 to engage the opposite arm 14, holding it until, by passage of the last unit of a group, the inwardly deflected arm is released, and will swing outwardly, elevating the latch 20. Both arms then being free by lifting action of the cam terminal, either is then subject to inward pressure of a unit, with simultaneous locking of the other arm.

Normally, in inactive position, as in Fig. 3, with both cam terminals raised and abutments 22 elevated, either arm may be pressed inwardly with locking of the other arm, as described.

In utilizing the switch as a divider, assuming reversal of conveyer travel, to divide a stream of units moving on conveyer section D towards the widening throat, and for separation to either or both of the conveyer sections A and B, the same means may be used.

In such case, with the arms 14 normally separated, approaching units will not pass to either branch conveyer automatically, unless the arms 14 and their shoes 16 are together, and at one side of the center, as in Fig. 1. In such position the terminals will then act as a deflecting common end point or horn, as in my prior Patent No. 2,168,191 (see end point 19), opening passageway to one branch conveyer and closing entrance to the other.

In such application, instead of automatic movement of one of the arms by unit contact with shoulder 15 and shoe 16, as in combining, one of the arms may be retracted towards the

other by any suitable means, the other arm becoming locked, as before.

One such means is illustrated diagrammatically in Fig. 9 in which each arm 14 is connected, as by rod 25, with a suitable prime mover, as the armature of a solenoid magnet 26, each being energized by a circuit controlled by suitable switch 27.

Otherwise, the construction is as above described, except as to such or other available means for positively locating one of the arms and its deflecting shoe for clearance to the utilized branch conveyer. Thus assuming one of the arms is deflected towards the other, as in Fig. 1, from its outer position, as indicated in Fig. 6, units will pass as indicated by the arrows. Alternate operation, by alternating magnet control, or other suitable means, may be utilized at intervals as desired, dependent on the required distribution of the units, in dividing them.

The construction and operation of the invention will be readily understood from the foregoing description. The switching section C, as a unitary assembly, may be readily installed in connection with already existing systems, or initially as a part thereof. It is simple, cheap, efficient and effective in group transfer of cylindrical articles, such as glass milk bottles, avoiding grinding or breakage, and in a combiner assembly, is continuously automatic. As a divider assembly, it is semi-automatic.

Various changes, alterations or modifications may be made by the skilled mechanic in adapting the invention to local or special conditions, or in particular features or details, within the scope of the following claims.

What I claim is:

1. A switch assembly for combining units of one conveyer with those of another for distribution to a single conveyer, consisting of a pair of resiliently held side-by-side approximately parallel arms each having an inwardly inclined deflecting fender and an outwardly projecting unit-arresting shoulder, and means whereby when one of the arm terminals is deflected towards the other, said other arm will be held outwardly.

2. A switch assembly comprising two conveyers merging into a single conveyer and having direction controlling guides, a pair of laterally movable arms in generally parallel relationship between the said two conveyers each having an inwardly sloping terminal fender disposed towards the single conveyer adapted when together to assume wedge-like formation, resilient means normally separating the arms and their fenders, and means for locking one of the arms when the other is thrust inwardly.

3. A switch assembly comprising a supporting frame for two conveyer trackways merging into a single conveyer trackway and having direction controlling guides all connecting with corresponding trackways and guides at opposite ends thereof, a pair of approximately parallel laterally movable arms between the two trackways each having a terminal fendering portion disposed towards the single trackway and an arresting abutment, resilient means normally separating the arms and their terminals, and means for locking one of the arms when the other is thrust inwardly.

4. A switch assembly comprising a supporting frame for two conveyer trackways merging into a single conveyer trackway and having direction controlling guides all connecting with corresponding trackways and guides at opposite ends there-

of, a pair of pivotally mounted approximately parallel laterally movable arms between the two trackways each having a rearwardly disposed shoulder and a terminal inclined shoe disposed towards the single trackway, springs normally separating the arms and their terminals, and a locking device supported upon and releasable by one of the arms when thrust inwardly and having an abutment adapted to engage and hold the other arm in its initial position.

5. In combination with a pair of laterally movable approximately parallel arms as described, means preventing movement of one of the arms towards the other consisting of two oppositely disposed locking members arranged transversely of the arms each having a holding abutment engageable with one arm and a terminal portion engageable by the other arm to hold the locking member and its abutment in unlocking position or to release same to effect locking.

6. In combination with a pair of laterally movable arms as described, means preventing inward movement of one of the arms consisting of two oppositely disposed locking members each pivoted at one end for vertical movement and having a terminal cam and an intermediate holding abutment, both normally being elevated by outward movement to normal position and cam engagement by said arms, either of said locking members lowering by gravity upon inward movement of its supporting arm and effecting holding engagement by its abutment with the other arm.

7. A switch assembly comprising two conveyers merging into a single conveyer and having direction controlling guides, a pair of approximately parallel adjacent laterally movable arms between the said two conveyers each having an inwardly inclined terminal fender disposed towards the single conveyer, resilient means normally separating the arms and their fenders, and operatively connected means for thrusting one of the arms inwardly.

8. A switch assembly comprising two conveyers merging into a single conveyer and having direction controlling guides for units in transit, a pair of approximately parallel adjacent laterally movable arms between the said two conveyers each having an inwardly inclined terminal fender disposed towards the single conveyer, resilient means normally separating the arms and their fenders, operatively connected means for thrusting one of the arms inwardly, and means for locking the other arm.

9. In combination, an actively propelling incoming conveyer having communicating junction with two outgoing divided branch conveyer sections through an intervening widened throat, a pair of laterally movable normally separated approximately parallel adjacent arms each having an inwardly sloping terminal portion confronting the incoming conveyer, and operatively connected means for moving one of said arms and its terminal towards the other to close the terminals together at one side in wedge formation and provide clearance and a laterally deflecting element for approaching units at the other side.

10. In combination, an actively propelling incoming conveyer having communicating junction with two outgoing divided branch conveyer sections through an intervening widened throat, a pair of resiliently separated laterally movable arms each having an inclined terminal portion confronting the incoming conveyer, means for moving one of said arms and its terminal towards the other to close the terminals together and pro-

vide clearance while presenting its terminal in position to serve as a laterally deflecting element for approaching units, and means for locking the other arm.

11. A switch assembly comprising two conveyors merging into a single conveyer and having direction controlling guides, a pair of approximately parallel laterally movable arms between the two conveyers each having an inclined terminal fender confronting the single conveyer, means normally separating the arms sufficiently to extend each terminal fender partly across the associated one of said two conveyers while permitting either arm to be freely movable inwardly towards the other, and means for locking said other arm when its companion arm is moved towards it.

12. A switch assembly comprising two conveyers merging into a single conveyer and having direction controlling guides, a pair of approximately parallel laterally movable arms between the two conveyers each having an inclined terminal fender confronting the single conveyer, means normally separating the arms sufficiently to extend each terminal fender partly across the associated one of said two conveyers while permitting either arm to be freely movable inwardly towards the other, and means for locking said other arm when its companion arm is moved towards it and for unlocking it when the companion arm is reversed.

CHRISTIAN N. BERGMANN.
